UNITED STATES PATENT OFFICE.

CHRISTIAN E. SKYUM, OF CHICAGO, ILLINOIS.

SCOOP.

1,074,474.

Specification of Letters Patent. Patented Sept. 30, 1913;

Application filed December 3, 1910. Serial No. 595,504.

To all whom it may concern:

Be it known that I, CHRISTIAN E. SKYUM, a resident of Chicago, in the county of Cook and State of Illinois, have invented certain new and useful Improvements in Scoops, of which the following is a full, clear, and exact description.

The invention relates to scoops, such as are generally used by grocers for handling material in bulk, and designs to provide an improved scoop, having a diaphragm which is adapted to be conveniently manipulated to vary the amount of the load, which the scoop will hold, and to provide a scoop of improved construction.

The invention consists in the several novel features hereinafter set forth, and more particularly defined by claims at the conclusion hereof.

In drawings, Figure 1, is a perspective of a scoop embodying the invention. Fig. 2 is a central longitudinal section. Fig. 3, is a section taken on the line 3—3 of Fig. 2. Fig. 4, is a detail perspective of scraper for removing the excess material from the scoop. Fig. 5, is a section on line 5—5 of Fig. 2. Fig. 6, is a perspective of the adjustable slide for carrying the diaphragm. Fig. 7, is a detail perspective of a portion of the diaphragm and one of its guides. Fig. 8, is a central longitudinal section illustrating a modified form of the invention. Fig. 9, is a section taken on line 9—9 of Fig. 8.

The scoop comprises a body 10, consisting of a fixed back 11, a curved bottom 12 and sides 13. A hollow handle 14 is secured to and projects outwardly from the back 11 of the scoop. A finger-grip 40 of wire is secured to the back 11.

A longitudinally adjustable diaphragm 15 extends across the space in the scoop-body in substantially parallel relation to the fixed back 11, and by longitudinal adjustment of the diaphragm, the quantity of material which the scoop will hold, may be varied. This diaphragm is mounted on a slide member 16, which is provided at its sides with tongues or guides 17, adapted to fit around the beaded or reinforced edges 18, of the sides 13 of the scoop. A V-shaped stem 19 is secured to the back of slide 16, and is adapted to extend into a guide 20 in the hollow handle 14, to guide the slide 16 longitudinally in conjunction with tongues 17.

A yielding strip 21 is secured in stem 19 and has an angular end 22 which is adapted

to engage the fixed back 11 to limit the outward longitudinal movement of slide 16, and prevent accidental disconnection of the slide from the scoop. When it is desired to remove the slide from the scoop, the yielding terminal 22 may be pressed upwardly to clear the back 11, which will permit the slide to be disconnected from the body of the scoop.

The diaphragm 15, is slidably mounted on slide 16 so that its edges will fit snugly against the bottom and sides of the scoop, to prevent the material from passing into the space in back of the diaphragm, and the latter is held in such position by a spring 24, which has one of its terminals applied to press the diaphragm downwardly. The diaphragm is held to slide relatively to and on slide 16, by tongues 25 formed on the said slide, extending around the edges of the diaphragm and fitting against the front face thereof; the back side of the diaphragm fitting against the front face of the vertical wall of slide 16. A slot 26 is formed in the vertical wall of slide 16 through which the terminal of a spring 24 extends, and said spring extends through and holds the diaphragm in operative position. Resultantly the diaphragm is adapted to slide to and from the bottom of the scoop so that its edges will be free to permit the diaphragm to be adjusted longitudinally of the scoop.

Slide 16 is held against longitudinal movement in the scoop by clamping-means, consisting of a rod 27 which is pivotally mounted in ears 28, formed on slide 16, and has an arm 29 at each end which is adapted to engage the inner face of one of the reinforced edges 18 of the scoop-sides, to force said edges outwardly to clamp them in guides 17.

Rod 27 is off-set as at 30 to provide means whereby the clamping-arms may be rocked away from the edges of the scoop. One of the terminals of coil spring 24 is applied to off-set portion 30 of the rod to normally press arms 29 against edges 18 of the scoop. When off-set portion 30 of the clamping-rod 27 is pressed toward the diaphragm, against the force of spring 24, the slide 16 will be released and free to be shifted longitudinally of the scoop-body. A stud 31 is secured to the front of and projects forwardly from the diaphragm to serve as means whereby the diaphragm may be moved away from the bottom of the scoop against the force of

spring 24. Coil spring 24 thus serves to operate the clamping-means for holding the slide against longitudinal movement, and to hold the diaphragm in operative position.

5 In use, the diaphragm and the slide may be conjointly released, by pressing the thumb against off-set portion 30 of the clamping-rod 27, and by placing the forefinger around stud 31 and lifting the stud 10 upwardly and pressing portion 30 forwardly, and thus the diaphragm and slide may be conveniently and conjointly released, and when held in released position the diaphragm and slide may be adjusted 15 longitudinally of the scoop to vary the amount of the material which will be held therein.

In practice it is desirable to avoid over-loading of the scoop so that no more than 20 the pre-determined load will be held in the scoop. In handling material such as flour, it frequently occurs that the material is heaped higher than the scoop edges, and it is desirable to remove the excess of material. A 25 convenient device for this purpose consists of a scraper 33, which is slightly wider than the scoop, and is adapted to slide upon the scoop-edges, being provided with projecting lips 34, to fit around said edges. 30 In order that this scraper will at all times be readily accessible for use when desired, it is detachably connected to the scoop by means of a spring fastening-device, consisting of a button 35 secured to the front 35 of the diaphragm and a hole 36 in the scraper.

The spring-button 35, when forced through hole 36, detachably secures the scraper to the diaphragm. When the 40 scraper is to be used, it may be forced off said button and will then be free to be drawn over edges 18 of the scoop and to remove the excess material. Resultantly, this detachable scraper provides accessible and 45 easily operable means for removing the excess material from the scoop. A scale 41 is marked on stem 19 to indicate the capacity of the scoop, when the diaphragm is in different positions.

50 A modified form of the invention is illustrated in Figs. 8 and 9, in which a diaphragm 15' is pivotally sustained on a slide 16'. A wire 37 is secured to the back of diaphragm, and has its terminals 38 pivotally held in ears 39 formed on the slide. A flat spring 40' has one of its ends applied to off-set 30 of the clamping-rod 27 and its other end applied to press the diaphragm into position, to cause its edges to fit 55 against the bottom and sides of the scoop-body. To release the diaphragm and slide for longitudinal adjustment, the upper portion of the diaphragm, and off-set 30 of the clamping-rod will be pressed together. The 60 clamping arms 29 will then be swung away 65

from the scoop-edges 18, and the diaphragm will be swung about its pivots 38, so that its lower portion will move away from the bottom of the scoop.

The invention thus provides an improved 70 adjustable scoop, which may be quickly and easily adjusted to adapt it to hold different quantities of material.

Having thus described the invention, what I claim as new and desirable to secure by 75 Letters Patent, is;

1. A scoop comprising a body for holding the material, a member slidably mounted on the body, a diaphragm carried by and movably mounted on said member, and clamping-means for securing said member against longitudinal movement in the body, mounted on said member and disposed to engage said body. 80

2. A scoop comprising a body for holding 85 the material, a member slidably mounted on the body, a diaphragm carried by and movably mounted on said member and spring-operated clamping-means for securing the member against longitudinal movement in 90 the body, mounted on said member and disposed to engage said body.

3. A scoop comprising a body for holding 95 the material, a member slidably mounted on the body, a diaphragm carried by and movably mounted on said member, and clamping-means mounted on said member and disposed to engage the sides of said body.

4. A scoop comprising a body for holding 100 the material, a member slidably mounted on the body, a diaphragm carried by said member and clamping-means for securing said member against longitudinal movement on the body, comprising a rod pivoted on said member and having arms for engaging 105 the sides of the body.

5. A scoop comprising a body for holding 110 the material, a member slidably mounted on the body, a diaphragm carried by said member and clamping means for securing said member against longitudinal movement on the body, comprising a cross-rod pivoted on said member and having arms for engaging the sides of the body, and a spring for operating said arms. 115

6. A scoop comprising a body for holding 120 the material, a member mounted to slide longitudinally on the body, and a diaphragm slidably mounted on said member so that its lower edge may be shifted transversely of and away from the bottom of the body.

7. A scoop comprising a body for holding 125 the material, a member slidably mounted on said body, a diaphragm slidably mounted on said member, so that its lower edge may be shifted away from the bottom of the body, and a spring for holding said diaphragm against the bottom.

8. A scoop comprising a body for holding 130 material, a member slidably mounted to

move longitudinally on the body, means for securing said member against longitudinal movement, and a diaphragm slidably mounted on said member so that its lower edge 5 may be shifted away from bottom of the body.

9. A scoop comprising a body for holding the material, a member slidably mounted to move longitudinally on the body, clamping-10 means for securing said member on the body, mounted on said member, and a diaphragm slidably mounted on said member so that it may be shifted away from the bottom of the body.

10. A scoop comprising a body for holding the material, a member slidably mounted to move longitudinally on the body, a dia-20 phragm mounted on said member so that its edge may be shifted away from the bottom 20 of the body, clamping-means for securing said member on the body, and a spring applied to hold the diaphragm against the bottom and to operate the clamping-means.

11. A scoop comprising a body for holding the material, a member slidably mounted to move longitudinally on the body, clamping-means for securing the member on the body, a diaphragm slidably mounted on said member so that its edge may be moved away 25

from the bottom of the body, and a spring 30 applied to hold the diaphragm against the bottom and to operate the clamping-means.

12. A scoop comprising a body for holding the material, a diaphragm adjustably mounted in the scoop, a scraper for removing the excess material, and a friction-device for detachably securing the scraper so that it will be adjustable with the dia-35 phragm.

13. A scoop comprising a body for holding the material and a handle, a member slidably mounted on the body and having hook portions fitting around the edges of the scoop, and a diaphragm mounted to slide 40 on said member. 45

14. A scoop comprising a body for holding the material and a hollow handle, a member slidably mounted on the body and having guides for engaging the sides of the body, a stem on said member extending into 50 said handle, a yielding stop on the stem acting to limit outward movement of the stem, and a diaphragm mounted on said member.
